UNITED STATES PATENT OFFICE.

THOMAS COOPER DE LEON, OF WASHINGTON, DISTRICT OF COLUMBIA.

DUPLICATE-WHIST APPARATUS.

SPECIFICATION forming part of Letters Patent No. 653,665, dated July 17, 1900.

Application filed April 16, 1900. Serial No. 13,069. (No model.)

To all whom it may concern:

Be it known that I, THOMAS COOPER DE LEON, a citizen of the United States, residing at Washington, in the District of Columbia, 5 have invented a new and useful Improvement in Duplicate-Whist Apparatus, of which the following is a specification.

My invention relates to the convenient and proper separation and distribution of decks 10 of cards for whist-playing, the said decks or packs being subdivided into four hands for the game known as "duplicate whist," the intention in the present instance being to provide a convenient apparatus for keeping the 15 divided decks in their proper places, so that each hand comes before the players in turn and rotation, and means also for score-keeping in connection therewith and for duplicating the same.

20 My invention contemplates the employment of disks mounted on axes, each disk containing probably twelve hands of whist-cards, said disks being made, preferably, of hard wood about three - sixteenths of an inch thick. 25 These disks are provided with spaces, the spaces being separated by angular blocks of wood constructed so as to be slightly higher than the packs of cards they are intended to separate, and the said blocks are provided 30 with beveled edges on their exposed faces, as will be explained, to hold the cards firmly in place; but in addition thereto I provide a spring-holder near the rear of the pack. I provide also means for holding the pack or 35 deck near the edge of the disks. These disks are four in number and are mounted on axes provided with small cog-gearings, fixed to or integral therewith, and located between these cog-gearings and central thereof is the larger 40 gearing, intermeshing therewith and operated by suitable means. Means also are provided for locking the disks in fixed position after they have been shifted or moved to the desired point. A pointer is also provided, and 45 a novel method of scoring forms a part of the apparatus.

Referring to the accompanying drawings, which form a part of this specification, Figure 1 is a perspective view of my improved duplicate-whist apparatus. Fig. 2 is a cross-section on the line 2 2, Fig. 1. Fig. 3 is a detail view of one of the disks. Fig. 4 is a sectional

view of the counting apparatus. Fig. 5 is a detail view of the larger or master cog-wheel, showing the manner of its operating the 55 smaller cog-wheels. Fig. 6 is a detail cross-section of the hub and axle of the master cog-wheel.

In the drawings, *a b c d* are revoluble disks, and I have shown in Fig. 3 the detail plan 60 view of such a disk. These disks are preferably made of thin wood, as before stated, and are arranged to hold and contain twelve hands of whist-cards.

e are angular blocks made slightly higher 65 than the cards and are located so as to space the disks off in such a manner as to provide rectangular receptacles for the cards of the proper shape and dimensions. These blocks are provided with bevel-shaped edges, (see 70 Figs. 1 and 2,) which beveled edges serve to hold and retain the hands in position. I also provide near the edge of the disk a flat metal slide *f*, that is adapted to slide into the wooden blocks *e*, a slot being provided therefor. These 75 slides are numbered from "1" to "12," respectively, from left to right. As each slide is pressed in to release the hand of cards the thumb and finger of the player draw the hand from the disk at the front. When this 80 is done, the slide is shifted into the slot provided, and when the hand is returned to its place after having been played and counted the slide still remains concealed, thus leaving the particular hand unnumbered to indicate that it has been played. These disks 85 *a b c d* revolve from right to left. Each disk is provided with cog-wheels *g*, over which they fit and to which they are secured by means of a square shoulder *h*. The cog- 90 wheels *g* are secured by and turn upon pins *j*. They intermesh with the larger or master cog-wheel *k*. This latter cog-wheel revolves from left to right, being provided with and adapted to be turned by a pawl and ratchet 95 *l m*, that in operation will turn the disks *a b c d* one-twelfth around at each working of the ratchet. The pawl is mounted on arm *n*, the latter, as well as the ratchet *m* and the master cog-wheel *k*, turning loosely on the 100 main centero. A spring *p* serves to keep the pawl in place, and a cord *q*, controlled by a return-spring *r*, provides means of operation. The disks are arranged in pairs, one pair over

the other, so that in rotating they will not come in contact with one another. For shuffling purposes the disks may be removed by lifting the top T of the table, and thus 5
5 moving the disks from the attaching-axes. The disks and the cog-wheels may be made of hard wood or metal, as may be preferred.

A deal-indicator s is shown in Figs. 1 and 2 and is in the form of an arrow or index-finger affixed in the center of the top of the table. It is provided with an easy movement 10 on its pivot t , which latter is provided with four rectangular arms radiating therefrom and close beneath the top T of the table. As 15 the disk a revolves these arms are successively caught by the pins u and the arrow or indicator is given a quarter-revolution.

Score-counters are provided at r . They are small revolving cylinders of metal numbered from "1" to "13" and are set opposite to line of figures from "1" to "12," running down the side, so as to provide means for scoring the opposed sides or partners. As the hand is played these figures are turned 25 to the proper number of tricks and stand during the game. A second and small revolving marker is set close to the right of the first. This is to mark the gains of each hand on the duplicate plays.

30 The bottom w of the table proper, which holds the mechanism, rests upon a false bottom x , with a pivot O so arranged as to per-

mit it to revolve one-quarter of a circle and lock automatically at z . This serves to duplicate the hands according to the rules of the 35 game.

Having thus described my invention, the following is what I claim as new therein and desire to secure by Letters Patent:

1. A duplicate-whist apparatus hereinbefore described, consisting of four revoluble disks mounted on standards as shown, and overlapping but not interfering with one another and provided with cog-wheels at the lower end of the pivots with a master cog-wheel adapted to operate substantially as and for the purpose set forth. 40

2. In a duplicate-whist apparatus or table a series of four disks having receptacles for twelve hands of cards, means for retaining 50 said hands in position, means for rotating the disks a quarter-revolution and means for holding the disks in proper place.

3. A duplicate-whist apparatus as hereinbefore described, a series of four disks provided with cog-wheels, a master cog-wheel for turning the same and an indicator adapted to operate substantially as and for the purposes set forth. 55

THOMAS COOPER DE LEON.
